UNITED STATES PATENT OFFICE.

GEORGE C. HALE AND FREDRICH OLSEN, OF DOVER, NEW JERSEY.

METHOD FOR PREPARING PROPELLANT POWDER.

No Drawing.

Application filed November 6, 1923. Serial No. 673,128.

(GRANTED UNDER THE ACT OF MARCH 3, 1883; 22 STAT. L. 625.)

To all whom it may concern:

Be it known that we, GEORGE C. HALE and FREDRICH OLSEN, citizens of the United States, and residents of Dover, in the county of Morris and State of New Jersey, have invented an Improvement in Methods for Preparing Propellant Powder, of which the following is a specification.

The invention described herein may be used by the Government, or any of its officers or employees in prosecution of work for the Government, or by any other person in the United States, without payment to me of any royalty thereon, in accordance with the act of March 3, 1883.

The present invention relates to a method for preparing propellant powder.

The primary object of our invention is the establishment of a method for incorporating nitroguanidine into nitrocellulose powders.

With the foregoing and other objects in view, our invention resides in the novel combination of ingredients and in the details of preparation hereinafter described and claimed, it being understood that changes in the precise embodiment of the invention herein disclosed may be made within the scope of what is claimed without departing from the spirit of the invention.

Nitroguanidine has many properties which indicate its suitability for use as a propellant. For example, it is very stable, is non-hygroscopic, is easily ignited and burns quietly without leaving any appreciable residue. It is, however, a crystalline compound which cannot be colloided by any known solvent to produce a propellant powder similar to colloided nitrocellulose. It is soluble, however, in certain organic compounds which serve as colloidizing agents for nitrocellulose.

It is the purpose of our invention to use certain materials which serve as solvents for nitroguanidine and which at the same time may be employed as colloidizing agents for nitrocellulose as a means for carrying nitroguanidine into a nitrocellulose colloid.

Experiments have been conducted with a

number of organic materials which serve as solvents for nitroguanidine and which also serve as colloidizing agents for nitrocellulose. Thus, for example, it has been found that paratolylmethylketone, benzaldehyde, diacetin, and urethane, may be employed to produce, when nitroguanidine is mixed with nitrocellulose, a propellant which will have properties similar to colloided nitrocellulose. Such mixtures have been found to give excellent results ballistically and at the same time the mixture of the nonhygroscopic nitroguanidine with the ordinary hygroscopic nitrocellulose will almost entirely obviate any danger of deterioration of the propellant thus prepared due to moisture and dampness.

It is the object of our invention, then, to carry nitroguanidine into a nitrocellulose colloid by employing certain materials which serve both as solvents for the nitroguanidine and as colloidizing agents for nitrocellulose.

Wherever the word solvent is used throughout the specification or in the appended claims, the solvents paratolylmethylketone, benzaldehyde, diacetin, and urethane, are the only solvents intended to be included in such term.

We claim:

1. A method of incorporating nitroguanidine into a nitrocellulose powder which includes treating nitroguanidine with a solvent which serves both as a solvent for the nitroguanidine and as a colloidizing agent for the nitrocellulose.

2. A method of incorporating nitroguanidine into a nitrocellulose powder which includes dissolving the nitroguanidine in a solvent and then colloiding nitrocellulose with the solution.

3. A method of incorporating nitroguanidine into a nitrocellulose powder which includes treating a mixture of nitroguanidine and nitrocellulose with a solvent for the nitroguanidine which acts as a colloidizing agent for the nitrocellulose.

GEORGE C. HALE.
FREDRICH OLSEN.
